Inventor:

Franz Skaupy,
by *Abraham S. Fink*,
His Attorney.

UNITED STATES PATENT OFFICE.

FRANZ SKAUPY, OF BERLIN, GERMANY, ASSIGNOR TO GENERAL ELECTRIC COMPANY,
A CORPORATION OF NEW YORK.

ELECTRIC LAMP.

Application filed December 11, 1922, Serial No. 606,173, and in Germany December 21, 1921.

My invention relates to electric glow lamps. It relates for example to glow lamps in which a current conveying metallic light-giving element which may be tungsten or the like is mounted or spread on a suitable support.

Heretofore, in lamps of the above type, the support element has been of a refractory material which is a non-conductor of heat or at best a poor conductor and which is non-transparent. Thorium oxide has sometimes been used for this support. Such lamps of the prior art have been inefficient because of the great losses due to convection inasmuch as these lamps are provided with gases.

My invention contemplates having the support element made of transparent material which will convey sufficient heat to the light-giving element mounted thereon to make the element luminous and yet the body on which the element is mounted does not interfere materially with the radiation of the light-giving element enabling the light-giving element to stand out.

My invention also contemplates the production of a lamp which consumes a much smaller portion of current than similar lamps have heretofore consumed to accomplish a given result. The lamps of the prior art have been very inefficient because the opaque body upon which the luminous element is mounted, being comparatively large, causes a large amount of loss due to convection and black radiation, so called.

My invention also contemplates other details of improvement tending to increase the efficiency and serviceability of a lamp of the above character.

The means for accomplishing the foregoing ends are hereinafter more fully disclosed and claimed.

Referring to the accompanying drawing, Fig. 1 shows one of the lamps of my invention in elevation; Fig. 2 shows a modified construction of the lamp.

The metallic light emitting element can be spread over the transparent support in any suitable form, as for example, in the form of hands, letters, figures or the like. In order to obtain a coating of the light emitting element in any particular form any one of the various known methods may be used such as, for example, the cathode atomization method. In such cases a stencil provided with corresponding openings is placed

over the transparent support during the atomization with the result that a coating is produced on the transparent support conforming to the form of a stencil. Special effects can be obtained if the metallic conductor or light giving element, formed as a layer, is made in the form of letters, pictorial representations or the like inasmuch as the transparent support, although it may have approximately the same temperature as the light giving element, does not emit light or emits very little. This would not be the case with a non-transparent support. A strip of the light emitting element of metal mounted on the support is included in an electric current circuit. The current of course, heats the conducting metal and therefore the transparent support is heated to approximately the same temperature as the current traversed conductor. Therefore, other sections of metallic light emitting material may be mounted on the transparent body and although not traversed by an electric current, will nevertheless light up as a result of the heat conduction through the transparent body. Such a construction is shown in Fig. 1. In this figure I show a globe *a* similar to the ordinary incandescent lamp globe. In the interior there is provided a base *b* through which the inlet wires *c* pass in the usual manner. The current inlet wires *c* serve at the same time to hold the rectangular transparent plate *d* which carries the current metallic lighting element *e*. This element *e* is in the form of a rectangular frame and may consist of tungsten. Within the frame there is arranged on the surface of the plate *d* another metallic coating *f* which appears in the form of the word "Osram". This section of the coating is not electrically connected with the frame nor with the electric circuit. In the operation of the lamp, the coating *e* not only emits light, but also serves to heat the support plate *d* which does not light up or which, if it lights at all, does so to a very small degree. As a result, the coating *f* stands out as an illuminated word.

In the form of lamp shown in Fig. 2, the transparent support which is held by the current inlet wires *c* consists of a small rod *g* on which is wound, in helical form, a wire-like conductor *h* of tungsten, for example. The transparent support may be made either of glass or of any transparent material con-

sisting of one or a few crystals. The following substances, for example, may be used: the difficultly fusible oxides such as thorium oxide, quartz and the like; also the 5 nitrate or carbide of thorium.

It will be seen, therefore, that I provide a glow lamp which is highly efficient inasmuch as the heat losses due to convection are reduced to a minimum and in which the 10 light emitting element stands out without being blurred to any material extent by light emanating from the supporting element. Such a lamp therefore is not only efficient as an electric sign or the like but 15 is also economical in its operation inasmuch as it consumes a comparatively small amount of current.

What I claim as new and desire to secure by Letters Patent of the United States, is:

20 1. In an electric glow lamp, in combination, a support, a heating element and a light emitting element on said support, said heating element adapted to be heated to in-

candescence by current from a suitable source whereby the support may be heated, 25 said support serving in turn as a heating element for the light emitting element to cause the latter to glow, said support being transparent and having a macrocrystalline structure.

2. In a glow lamp, a transparent support, a light emitting body isolated on said support, independent means for heating the transparent body whereby the latter in turn 30 may heat the isolated body to cause the latter to emit light.

3. In a glow lamp, a transparent support, a light emitting body isolated on said support, independent means for heating the transparent body whereby the latter in turn 35 may heat the isolated body to cause the latter to emit light, said transparent body being macrocrystalline.

In witness whereof, I have hereunto set my hand this 21st day of November, 1922.

FRANZ SKAUPY.
